UNITED STATES PATENT OFFICE.

EDWARD W. COMFORT, OF WINCHESTER, AND ALBERT W. THOMPSON, OF LOWELL,
MASSACHUSETTS, ASSIGNEES TO PARKS-CRAMER COMPANY, OF BOSTON, MASSA-
CHUSETTS, A CORPORATION OF MASSACHUSETTS.

THERMOSTATIC REGULATOR.

Application filed June 11, 1923. Serial No. 644,555.

To all whom it may concern:

Be it known that we, EDWARD W. COMFORT and ALBERT W. THOMPSON, both citizens of the United States, residents of Winchester, county of Middlesex, State of Massachusetts, and of Lowell, county of Middlesex, State of Massachusetts, respectively, have invented an Improvement in Thermostatic Regulators, of which the following description, in connection with the accompanying drawing, is a specification, like characters on the drawing representing like parts.

This invention relates to improvements in thermostatic regulating devices of the type broadly disclosed in the patent to Stuart W. Cramer and William B. Hodge No. 1,331,981 granted February 24, 1920 which comprises two independently mounted thermo-expansive members each arranged to respond separately to the temperature to which it is subjected, a lever system operated by such thermo-expansive members and means controlled solely by the differential action of the thermo-expansive members through said lever system to control an external source of power which regulates other mechanisms such, for example, as the means for supplying moisture to the air or means for regulating the temperature of an enclosure.

Numerous other patents have been granted covering mechanisms embodying this broad principle; such, for example, as Patent No. 1,231,570 granted July 3, 1917 to Stuart W. Cramer and William B. Hodge, and Patent No. 1,228,718 granted June 5, 1917 to Albert W. Thompson and Edward W. Comfort.

In the constructions disclosed in these patents means are provided for setting the instrument at a predetermined wet bulb depression at any desired dry bulb temperature and means are also provided for accomplishing the so-called "ratio adjustment" which enables the instrument to operate upon a basis of variable wet bulb depression. The purposes of such adjustments need not be further described herein as they are fully set forth in one or more of the patents above cited and are well known in the art and recognized as necessary to the satisfactory operation of such instruments.

Regulating devices of this type also include as an essential part a so-called "controlling device" which usually is in the form of separable contact members controlled by the movement of the thermostatic elements and which in turn controls an intermediate force utilized to operate the main valves which control vaporizing means for supplying moisture to the atmosphere, dampers which regulate the amount of air either in the atmospheric state or in the humidified condition which is introduced into the enclosure, or humidity and temperature conditions of drying apparatus, etc.

The intermediate force or source of energy which is usually commercially used is either compressed air or electricity, the controlling devices for which are respectively in the form of small pneumatic valves, or electric contacts used to make and break an electric circuit. Inasmuch, however, as the invention does not involve the particular form of the intermediate source of energy, the particular controlling device therefor, or the devices operated by the intermediate source of energy they need not be described herein.

In regulators of this type the thermo-expansive wet and dry bulb elements employed have been either of the longitudinally expanding bar type or the fluid expansion type. In the longitudinally expanding bar type of instrument the expansion of the wet and dry bulb elements due to varying temperature conditions of the atmosphere, are microscopic and involve the use of extremely delicate and sensitive mechanical apparatus. The thermo-expansive members of regulating instruments of the fluid expansion type produce relatively great movements, as compared with the longitudinally expanding bar type, when subjected to different temperature conditions, but are of difficult and necessarily expensive construction and not homogeneous or uniform in their characteristics.

The principal object of the present invention is to provide a regulator in which thermo-expansive members are employed which will produce relatively wide movements when subjected to different temperature conditions, but which will be relatively simple and inexpensive in construction.

A further object of the invention is to provide an instrument of this character with novel means for producing a desired wet bulb depression setting and also for providing a novel means for producing a ratio adjustment which will enable the instrument properly to produce the particular variable wet bulb depression necessary to maintain a predetermined condition of the air, such, for example, as constant absolute humidity, constant relative humidity, or variable relative humidity in accordance with the humidity laws upon which the tables of absolute humidity, relative humidity, cotton regain, etc., are based.

A further object of the invention is to provide means for more effectively insulating the wet bulb thermostatic member from the dry bulb thermostatic member so that the thermostatic members will be subjected respectively to the true dry bulb and the true wet bulb, or preferably the psychrometric wet bulb temperature of the air.

Other objects and features of the invention will more fully appear from the following description and the accompanying drawings and will be particularly pointed out in the claims.

A preferred embodiment of the invention is illustrated in the drawings, in which,

Fig. 1 is a front elevation of a thermostatic regulator embodying the invention, the front of the casing being removed;

Fig. 2 is a side elevation, viewed from the left, the casing being shown in dotted lines;

Fig. 3 is a vertical sectional view on line 3—3, Fig. 1;

Fig. 4 is an enlarged transverse sectional view through the insulating conduit and central portion of the wet bulb thermostatic member, showing also in elevation the rod through which the movement of the thermostatic member is imparted to lever mechanism for actuating an energy-controlling device, and in section the means by which the rod is connected to the thermostatic member and to the lever; and,

Fig. 5 is a vertical sectional view of the adjusting mechanism for setting the instrument to operate upon a predetermined wet bulb depression.

In the particular embodiment of the invention disclosed in the accompanying drawings the operative parts of the instrument are mounted upon a base 1, which desirably is made of a material which is a non-conductor of heat and which is not appreciably expandable by variations in temperature. The base desirably is provided with a peripheral flange 2 and a rib 3 extending in parallelism with the side flanges and one end flange providing a seat to receive the edges of the sides of a box-like rectangular cover 4 which fits upon the rib 3 and

forms a casing enclosing the operative parts of the instrument.

Suitable dowels 5, preferably extending upwardly from the corner portions of the rib 3, may be provided to enter complementary sockets in the cover to enable the cover to be easily and securely mounted upon the base, said cover being retained by suitable screws seated in screw holes 6 in bosses projecting from the rib 3. 75

Suitable partitions desirably are provided to divide the interior of the casing into a dry bulb chamber, a wet bulb chamber and an intermediate chamber containing the leverage mechanism and the energy-controlling device which is operated thereby. As illustrated these partitions comprise plates 7 and 8 extending in parallelism with the sides of the base or casing having respectively flanges 9 and 10 which rest upon the base and are secured thereto by suitable screws or other fastenings. A similar transverse plate 11, having a flange 12 secured to the base, connects the upper ends of the plates 7 and 8, to form the closed casing for the leverage mechanism, and is located at a sufficient distance from the upper end of the casing to permit an air passage from the dry bulb compartment to the wet bulb compartment so that a continuous sample of air from the room or enclosure may be drawn upwardly through the dry bulb compartment and saturated with moisture as it enters the wet bulb compartment. 80 85

One of the features of the present invention is to provide more perfect means for insulating the wet and dry bulb members from the influence of the temperature of the medium to which the other member is subjected. This is accomplished in the present construction by interposing between the wet and dry bulb chambers an intermediate chamber containing the leverage mechanism and the energy-controlling device and also by providing the wet bulb chamber with a tubular conduit having a highly insulated wall enclosing the wet bulb member providing a chamber in which the sample of air drawn through the dry bulb compartment is saturated and caused to envelop the wet bulb member. This conduit, as illustrated more particularly in cross section in Fig. 4, desirably is of channel-shaped rectangular cross section having outer and inner sheet metal walls 13 and 14 which are spaced apart and the interval between them filled with a fibrous material 15 which is a non-conductor of heat. The walls 13 and 14 desirably are united at their edges to form an integral structure and are provided with a reentrant channel or groove 16 adjacent the outer wall to receive the projecting edge 17 of the wall 18 of a cover plate having an inner wall 19 spaced apart therefrom adapted to seat upon the edge of 100 105 110 115 120 125 130

the channel-shaped body of the conduit. The space between the walls 18 and 19 of the cover likewise is filled with the fibrous non-conducting material 15.

5 In order to enable the operator to observe the temperature within the wet bulb chamber a suitable thermometer 20 may be secured to the cover plate with its bulb extending into the wet bulb chamber and a 10 similar thermometer (not shown) may be provided to indicate the temperature in the dry bulb chamber.

The wet bulb thermo-expansive element is subjected preferably to the psychrometric wet bulb temperature of the same sample of air that envelops the dry bulb thermo-expansive member. This is accomplished in the present invention by providing a suitable atomizer 21, preferably carried by the cover plate, which projects a spray through a tubular conduit 22 which is carried by a bracket 23 secured to the base, into the upper end of the insulated conduit which encloses the wet bulb member, said conduit and the rear of the casing being provided with a suitable aperture 24 to permit the moisture-laden atmosphere to be discharged and from which it may be conducted away from the vicinity of the 30 instrument by a tube, not shown.

One of the principal objects of the invention is to provide thermo-expansive or thermostatic members which will be more effective in operation and less sensitive to 35 vibrations of a mill or to shocks than instruments heretofore produced and also to provide a simplified leverage mechanism for transmitting the movements of the wet and dry bulb members to the energy-controlling 40 device. This is accomplished in the present invention by providing laterally distortion-al thermostatic members which are so mounted as to prevent lateral movement of the end portions of the members, but to per- 45 mit longitudinal movement thereof, and by providing means differentially operable by the lateral distortion movements of said members, intermediate of the supporting means, to actuate the energy-controlling de- 50 vice.

The thermostatic members may be constructed in any suitable manner and of any suitable material to accomplish these purposes. Preferably the members are in the 55 form of flat, bi-metallic bars or ribbons formed of two sheets of materials having different coefficients of expansion, the flat surfaces of which are welded together throughout their lengths.

60 Preferably these thermostatic members are formed of sheets of invar steel and brass thus welded together. Invar steel has a very low coefficient of expansion while brass has a high coefficient of expansion, thus a 65 thermostatic member is provided which is

extremely sensitive to variations in temperature and which will be appreciably flexed by relatively small variations in temperature.

An approximately straight or slightly curved thermostatic member or element of 70 this type, such as the bimetallic element of invar steel and brass may be properly defined as a thermo-flexible element because the distinguishing characteristic of such an element is the change in curvature which 75 results from its reaction to a change in temperature. Moreover, the effective movement of such an element may be properly defined as its deflection, meaning thereby the movement of a designated point or portion of the 80 element, such as its middle portion, with respect to some stationary reference such as an imaginary line connecting the ends of the element, in the case illustrated.

Thermal elements of this type which are 85 distorted by change in temperature differ materially in character from elements of the bar, bellows, or capsule type which may be said to suffer expansion or distortion in one direction only. Elements subject to distortion such as the type illustrated are subject to a change of shape in more than one direction and must therefore be so disposed, when utilized for the purposes disclosed herein, that while their motion is utilized 90 effectively in one direction or dimension, ineffective motion is permitted to take place without opposition in some other direction.

Thus in the case illustrated an initially straight or slightly curved element is supported at one end on a fixed pivot and is supported at the opposite end by a pivot free to move on the extended center line of the pivots without opposition, while the movements of the middle portion of the element 100 with respect to said center line, that is to say its deflection, are utilized as effective motion, the change in length being ineffective. It is obvious that the invention includes with equal force elements of a different nature but organized by similar methods for similar purposes; for instance the deflections of a Bourdon tube slightly curved initially and suspended at each end could 105 obviously be utilized for the same purpose and would in fact constitute an element of the same type and suitable for the purposes of this invention.

Another advantage of elements of this 115 type organized in the manner illustrated is the practical immunity from sympathetic vibration which is thus secured. If a flexible element of this type is fixedly supported at one end the deflections of the free end may be utilized as effective motion as has long 120 been practiced in the thermostatic art. Such a construction, however, exposes the element to sympathetic vibration by virtue of the inertia due to its own weight with respect to the tendency to vibrate about its fixed end. 125

The construction which is characteristic of this invention makes it possible to utilize elements of this type while at the same time successfully avoiding the objectionable 5 tendency to vibrate.

Any suitable means may be provided for securing the end portions of these thermo-flexible members against lateral movement while providing for longitudinal movement 10 due to the shortening or lengthening of the member as it is bent or warped and also for such longitudinal movement as is occasioned by the longitudinal expansion of the member. As illustrated herein the wet bulb 15 member 25 is fixedly secured at its upper end in a block 26 having trunnions which are mounted upon pivots 27 in laterally extending arms 28 of a stand 29 which is secured to the wall of the insulated conduit or 20 to the base 1 of the instrument. The lower end of the wet bulb thermo-flexible member is similarly fixedly secured in a block 30 having trunnions which are mounted upon pivots 31 in the arms of a horizontal yoke 32 which is mounted upon pivots 33 in arms 34 of a similar stand 35 which is secured to the base 1.

The dry bulb thermo-flexible member 36 is likewise rigidly connected at its upper end 30 to a block 37 having trunnions 38 which are secured by pivots 39 to the arms 40 and 41 of a stand 42 which is mounted upon the base in the dry bulb compartment and the lower end of the dry bulb member is similarly rigidly secured in a block 43 having trunnions 44 which are mounted on pivots 45 in horizontal arms of a yoke 46 having an extension 47 which is connected by pivots 48 to the upper end of a lever 49 which is 40 fulcrumed at its lower end upon a post 50 extending from the base 1 of the casing. The lever 49 desirably is provided intermediate of its ends with a rigid boss 51 from which an arm 52 projects laterally, the end portion 53 of said arm, which is preferably reduced in thickness, engaging an adjusting device by means of which the lever 49 may be rocked about its pivot to vary the position of the lower end of the dry bulb 45 and thermo-flexible member and thereby provide a wet bulb depression setting as will hereinafter be more fully described. A spring 54, secured to and wound upon the post 50 and having its free end secured to the boss 51 of the lever 49, acts normally to hold the end 53 of the arm 52 in contact with the adjusting device.

The preferred form of adjusting device which is illustrated in enlarged detail in 60 Fig. 5 of the drawings comprises a screw 55 which engages complementary threads in a preferably split boss 56 at the upper end of a post 57 which is secured to the base 1 of the instrument. By thus splitting the boss 56 after the same has been bored and screw

threaded the threads of the boss can be made to engage more firmly the threads of the screw by providing suitable means, such as a transverse screw for drawing the sections of the split boss together upon the 70 screw. The screw 55 desirably is provided with a cylindrical head portion 58 having recesses 59 to receive a spanner wrench for adjusting the same.

Means are provided for enabling a desirable adjustment of the wet bulb depression to be observed by securing to the head 58 of the screw a cylindrical dial 60 suitably indexed upon its periphery and securing upon the boss 56 of the post 57 an index 61 positioned to co-operate with the graduations upon the periphery of the cylinder 60.

The wet and dry bulb thermo-flexible elements, mounted as above described, are thus fixedly secured at their ends against lateral 85 movement, but permitted to move longitudinally, and the dry bulb element is provided with means for adjusting its initial position laterally to effect the desired wet bulb depression setting. It will, however, be understood that the wet bulb depression adjustment may be applied to the wet bulb member instead of the dry bulb member if 90 found to be desirable or convenient.

Any suitable leverage mechanism may be 95 provided for causing the conjoint movements or the differential lateral deflections, or warping movements, of the wet and dry bulb thermo-flexible members intermediate of their ends, to actuate a suitable energy-controlling device and also for providing ratio adjustments which will enable the instrument to operate in accordance with the laws of humidity above mentioned.

In the preferred embodiment of the invention illustrated herein two levers are provided which are respectively actuated by the lateral deflections of the wet and dry bulb members and an energy-controlling device is carried upon one of the two levers 100 and adapted to co-operate with means carried upon the other lever in such manner as to effect actuation by the conjoint or differential motion of the levers in response to the lateral distortional movements of the 105 elements.

The particular construction illustrated is provided with means for controlling a source of pneumatic energy, such as a bleeder pipe from a relay mechanism of a compressed air system operable to control the supply of moisture or temperature of an enclosure, but as such mechanism is well known it will not be described.

An air pipe 62 for the compressed air 125 leads through the base 1 of the instrument and is provided with a spiral coil which communicates at its end 63 with a suitable conduit 64 which extends lengthwise of a lever 65 and communicates with a conduit 130

66 in the base portion 67 of an energy-controlling device which is mounted upon the lower end of the lever 65. The conduit 66 communicates with a suitable outlet in 5 a port member 68 which is secured to the base member 67 and a gravity-operated valve 69 which is mounted upon pivots 70 upon a bracket 71 extending upwardly from the base member 67 serves normally to close 10 the port in the member 68. The valve member 69 is provided with an upwardly extending arm 72 by means of which the valve may be differentially operated by the movements of the thermo-flexible member as will 15 hereinafter be more fully described. The lever 65 is suspended at its upper end upon pivots 73 in arms extending from a post 74 which is fixedly secured to the base 1 of the instrument. The lever 65 is connected 20 intermediate of its ends to the central portion of the dry bulb thermo-flexible member by an extensible rod 75 which is flexibly secured to the thermostatic member in order that the longitudinal movement of the thermo-expansive member will not affect the 25 movement of the lever which is caused by the lateral distortional movement of the thermostatic element.

The rod 75 is provided with a screw 30 threaded end which engages the internal screw threads of a block 76 having a reduced end portion 77 provided with a spherical head which engages a complementary spherical seat in a boss 78 upon a hollow rectangular member 79 which is slidably mounted 35 upon the lever 64 and is adapted to be secured in adjusted position by a set screw 80 which passes through one of the sides of said rectangular member and abuts against 40 the lever 65. A tension spring 81, connected at its ends respectively to the base 71 of the energy-controlling device and to the partition wall 7, prevents lost motion between the ends of the rod 75 and the lever 65.

45 The actuation of the energy-controlling device is accomplished through a lever 82 which is suspended upon pivots 83 upon arms of a post 84 which is mounted upon the base 1, the central portion of said lever 50 being connected by a rod 85 to the central portion of the wet bulb thermo-flexible member 25. Similar flexible connections are provided between the ends of the rod 85 and the lever 82 and the wet bulb thermo-flexible 55 member 25 to those heretofore described with respect to the lever 65 and dry bulb thermo-flexible member 36, such connections being more fully shown in detail in Fig. 4.

60 As illustrated the rod 85 is provided with a reduced portion and terminates in a spherical end 86 which engages a suitable socket 87 in the central portion of the wet bulb member and is secured therein by a strap 88 which is fastened to the thermo-flexible 65 member and embraces the reduced portion

of the rod 85 adjacent the ball. The opposite end of the rod 85 is provided with screw threads which engage complementary internal screw threads in a block 89 which is provided with a reduced extension 90 having 70 a spherical end which engages a complementary socket in a sleeve 91 which is secured to the central portion of the lever 82 by a set screw 92. A tension spring 93, secured at one end to the lever 82 and at its 75 opposite end to the partition wall 8, prevents lost motion between the end of the rod 85 and the lever 82. The lower end of the lever 82 is provided with an arm 94 which extends over the upwardly extending arm 72 of the gravity valve 69 and has a downwardly turned or hook-shaped end 95 which is positioned to engage the arm 72 and actuate the lever upon a variation from a predetermined difference in the deflectional 80 movements of the thermo-flexible wet and dry bulb members 25 and 36.

In order to facilitate the cleaning of the valve, the arm 94 is rotarily mounted upon the lower end of the lever 82 so that it 85 can be swung aside to permit the position of the gravity valve 69 to be reversed and the port of the member 68 exposed for cleaning.

In the construction shown the arm 94 is 90 provided with an offset end 96 which is secured to a block 97 which is mounted upon pivots 98 engaging a sleeve which is rotatably mounted upon the cylindrical lower end of the lever 82. The block 97 has secured to it a keeper 99 having a slot which embraces a stud 100 extending from the lever 82, while a spring 101 on the opposite side of the lever engages the offset portion 96 of the arm 94 and serves normally to 100 maintain the end of the keeper 99 in contact with the lever 82. When it is desired to remove the arm 94 for the purpose of cleaning the valve port the arm 94 is first 105 swung upwardly until the keeper 99 is removed from engagement with the stud 100, whereupon the arm 94 may be swung about the axis of the lever 82 out of the path of the arm 72 of the gravity valve. The gravity valve can then be swung about its pivot 110 70 to expose the port of the member 68 so that the latter, and also the under surface of the valve, can be readily cleaned.

115 It will be understood that while a device for controlling a source of pneumatic energy is illustrated herein, means for controlling other sources of energy, such as electrical contacts may be employed. The valve members 68 and 69 may, therefore, be herein defined as contact members, since by moving them into and out of contact the source of energy may be controlled whether a pneumatic, an electric, or other source of energy is employed, for it is well known in 120 the commercial art that the same instrument 125

may be provided with suitable contact members to regulate either pneumatic, electric or other sources of energy.

In the operation of the device the spray from the atomizer, which is projected into the insulated conduit in the wet bulb compartment, induces a current of air through the dry bulb compartment and saturates the same with moisture as it enters the insulated conduit of the wet bulb compartment. The wet and dry bulb thermo-flexible members are, therefore, subjected to the influence of the same sample of air from the enclosure, the dry bulb member being subject to its normal temperature and the wet bulb member to the psychrometric wet bulb temperature thereof. The wet and dry bulb members will, therefore, be subjected to different temperatures except when the air entering the humidifier is in a saturated condition. Consequently, when the wet and dry bulb members are thus subjected to different temperatures their expansion will cause different degrees of deflection. The deflection of the dry bulb member, acting through the rod 75, will move the lever 65 about its pivot, thus moving the energy-controlling device which is supported at the end of the lever. The deflection of the wet bulb thermostatic member likewise acting through the lever 85 will swing the lever 82 about its pivot and will move the arm 94 relatively to the arm 72 of the gravity contact member or valve 69.

The thermostatic members as illustrated are so constructed and positioned that like changes in temperature will produce lateral distortion or displacement in the same direction in each, and similar motions in the levers in the same direction in each case will result. In the present construction this is accomplished by positioning the thermo-flexible elements with the brass sides thereof facing in the same direction. It is to be noted that in respect to their respective actuating effect upon the controlling device one of the members is positive in its actions and the other negative and that the effective relative motion resulting from the actions of the elements between the co-operating parts is the algebraic sum of those values which are imparted to the lever system by the original distortional movements of the respective elements. The device therefore possesses the fundamental characteristics of differential motion.

When the ratio between the two arms in one lever is the same as the ratio between corresponding arms of the other lever, the arm 94 of one lever and the arm 72 of the contact member will therefore move in unison and contact member 69 will suffer no effective change.

It is characteristic of this device that the tendency to produce actuation of the en-

ergy-controlling device as the result of a change in temperature in one element is rendered ineffective or neutralized by a like change of temperature in the other element, so that actuation can occur only when there is a difference in value between the movements of the arm 72 of the contact member on the one hand and the movements of the co-operating contact arm 94 on the other. It is clear therefore that the energy-controlling device is differentially operated by the lateral distortional movements or deflections of the thermostatic members which result from their reaction to changes in their respective temperatures. If, therefore, lateral distortion of the dry bulb member exceeds the lateral distortion of the wet bulb member, the arm 72 will be engaged by the end 95 of the arm 94 and will remove the contact member 69 from engagement with its complementary member 68, thereby opening the port of the air conduit 62, thus permitting the air to escape and actuating the pneumatic system which controls the supply of moisture or heat, as the case may be, to the enclosure.

By rotating the head 59 of the screw the arm 53 of the lever 49 which is connected to the lower end of the dry bulb thermostatic member may be swung to one side or to the other thus varying the position of the thermostatic member 36 and through the arm 75 the position of the lever 64 which supports the energy-controlling device, so that the arm 72 of the contact member 69 may be properly positioned with respect to the end 95 of the arm 94 upon the lever 82 which is controlled by the wet bulb thermo-expansive member to provide a proper wet bulb depression setting of the device, since by moving the arm 72 of the contact member toward or from the end 95 of the arm 94, actuation may thus be prearranged at any desired difference in deflection of the members which corresponds to any predetermined difference in their temperatures.

A similar wet bulb depression of the device can be accomplished by proper lengthening or shortening of the rods 75 or 85 or both of them, but the adjustability of the length of these rods is primarily for the purpose of enabling the instrument to be properly assembled.

The ratio adjustment is desirably accomplished by varying the position of the rectangular block 79 upon the lever 65. This is accomplished by unscrewing the screw 80 and sliding the block 79 lengthwise of the lever 65 until the proper leverage action upon the energy-controlling device is established, such ratio settings being indicated by reference graduations upon the lever 65, having previously been determined either by calibration if the two thermostatic elements are not perfectly matched or by cal-

culation if they have been matched. Similarly the proper leverage ratio may be provided by adjusting the sleeve 91 longitudinally of the lever 82 which is actuated from the wet bulb thermostatic member.

The desired ratio adjustment may also be conveniently provided by building into the instrument a permanent but predetermined relation between the effective leverages of the levers in which case the adjustable provision for the lever 65 may be omitted and the connection thereto of the rod 75 may be permanent; also the connection between the rod 85 and lever 81 may be permanent.

It will thus be observed that various means may be employed for accomplishing the ratio setting of the instrument. It will also be obvious that various other leverage systems may be substituted for those which are particularly described herein.

It will, therefore, be understood that the embodiment of the invention disclosed herein is of an illustrative character and is not restrictive and that various changes in form, construction and arrangement of parts may be made within the spirit and scope of the following claims.

Having thus described the invention, what is claimed as new, and desired to be secured by Letters Patent, is:

1. A thermostatic regulator comprising laterally distortional thermo-flexible members subject respectively to the dry and wet bulb temperatures of the air, supporting means for each of said members acting to prevent lateral movement of the ends thereof and an energy-controlling device differentially operable by the lateral distortional movements of said members.

2. A thermostatic regulator comprising laterally distortional thermo-flexible members subject respectively to the dry and wet bulb temperatures of the air, supporting means for each of said members acting to prevent lateral movement of the ends thereof, but to permit longitudinal movement of said members, an energy-controlling device differentially operable by the lateral distortional movements of said members and means for varying the positions of said energy-controlling device relative to one of said thermo-flexible members to provide a wet bulb depression setting of the device.

3. A thermostatic regulator comprising laterally distortional thermo-flexible members subject respectively to the dry and wet bulb temperatures of the air, supporting means for each of said members acting to prevent lateral movement of the ends thereof, but to permit longitudinal movement of said members, an energy-controlling device interposed between said thermo-flexible members differentially operable by the lateral distortional movements of said members intermediate of said supporting means

and means for relatively adjusting said thermo-flexible members laterally to vary the wet bulb depression setting of the device.

4. A thermostatic regulator comprising laterally distortional thermo-flexible members subject respectively to the dry and wet bulb temperatures of the air, supporting means for each of said members acting to prevent lateral movement of the ends thereof, but to permit longitudinal movement of said members, an energy-controlling device differentially operable by the lateral distortional movements of said members mechanically interposed between said supporting means and means for varying, in a predetermined ratio, the value of the effective distortional movement of one of said members relatively to that of the other upon said energy-controlling device.

5. A thermostatic regulator comprising laterally distortional bi-metallic thermo-flexible members subject respectively to the dry and wet bulb temperatures of the air, supporting means for each of said members acting to prevent lateral movement of the ends thereof, lever mechanisms connected to the respective members intermediate of their end portions operable by the deflections of said members, caused by changes in temperature, and an energy-controlling device differentially operable by the movements of said lever mechanisms.

6. A thermostatic regulator comprising laterally distortional bi-metallic thermo-flexible members subject respectively to the dry and wet bulb temperatures of the air, supporting means for each of said members acting to prevent lateral movement of the ends thereof, lever mechanisms connected to the respective members intermediate of their end portions operable by the deflections of said members, caused by changes in temperature, an energy-controlling device carried by one of said lever mechanisms and differentially operable by the movements of said lever mechanisms and means for adjusting the relative positions of said lever mechanisms to vary the wet bulb depression setting of the device.

7. A thermostatic regulator comprising laterally distortional bi-metallic thermo-flexible members subject respectively to the dry and wet bulb temperatures of the air, supporting means for each of said members acting to prevent lateral movement of the ends thereof, lever mechanisms connected to the respective members intermediate of their end portions operable by the deflections of said members, caused by changes in temperature, an energy-controlling device differentially operable by the movements of said lever mechanisms and means for varying relative leverages of said lever mechanisms upon said energy-controlling device.

8. A thermostatic regulator comprising laterally distortional bi-metallic thermo-flexible members subject respectively to the dry and wet bulb temperatures of the air, pivotal supports for one end of the respective thermostatic members and connections engaging the other ends of the respective thermo-flexible members operable to prevent lateral bodily movement of said members, but to permit longitudinal movement thereof, levers connected respectively to said dry and wet bulb thermo-flexible members intermediate of their ends, an energy-controlling device carried by one of said levers and means carried by the other of said levers differentially operable by the movements of said levers caused by the deflections of said thermo-flexible members to actuate said energy-controlling device.

10 9. A thermostatic regulator comprising laterally distortional bi-metallic thermo-flexible members subject respectively to the dry and wet bulb temperatures of the air, pivotal supports for one end of the respective members and connections engaging the other ends of the respective members operable to prevent lateral bodily movement of said members, but to permit longitudinal movement thereof, levers connected respectively to said dry and wet bulb thermo-flexible members intermediate of their ends, an energy-controlling device carried by one of said levers, means carried by the other of said levers differentially operable by the movements of said levers caused by the deflections of said thermo-flexible members to actuate said energy-controlling device and means for adjusting one of said connecting rods longitudinally of its lever to vary the value of the effective movements of said levers upon said energy-controlling mechanism in a predetermined ratio.

15 10. A thermostatic regulator comprising laterally distortional thermo-flexible members subject respectively to the dry and wet bulb temperatures of the air, pivotal supports for the upper end of the respective thermo-flexible members permitting lateral movement thereof, connections engaging the lower ends of the respective thermostatic members acting to prevent lateral bodily movement of said members, but to permit longitudinal movement thereof, levers pivotally supported at their upper ends connected to the central portions of the respective dry and wet bulb thermo-flexible members, an energy-controlling device carried by the free end of one of said levers comprising a base member and a co-operating relatively movable gravity-actuated contacting member and means connected to the free end of the other lever positioned to engage and remove said gravity-actuated contacting member from engagement with said base member upon a predetermined difference in the distortional movements of said dry and wet bulb members.

20 11. A thermostatic regulator comprising laterally distortional thermo-flexible members subject respectively to the dry and wet bulb temperatures of the air, pivotal supports for the upper end of the respective thermo-flexible members permitting lateral movement thereof, connections engaging the lower ends of the respective members acting to prevent lateral bodily movement of said members, but to permit longitudinal movement thereof, levers pivotally supported at their upper ends connected to the central portions of the respective dry and wet bulb thermo-flexible members, a pneumatic en-

ergy-controlling device comprising a conduit extending through one of said levers, a base member mounted upon the free end of said lever having a port, a gravity valve 5 pivotally mounted on said base co-operating with said port and normally closing the same and means upon the free end of the other of said levers positioned to remove said gravity valve from engagement with 10 said port upon a predetermined difference in the distortional movements of said dry and wet bulb members.

14. A thermostatic regulator comprising a casing having separated wet and dry bulb 15 compartments, co-operating bi-metallic wet and dry bulb thermo-flexible members mounted in said casing in the respective compartments, an energy-controlling device located intermediate of said wet and dry 20 bulb compartments, means connected to said thermostatic members differentially operable by the lateral distortional movements of said members, a conduit in said wet bulb compartment having insulated 25 walls enclosing said wet bulb thermo-flexible member and communicating at its upper end with the dry bulb compartment of the casing, means for producing a spray of water and projecting the same into the 30 upper end of said conduit, acting to induce a draft of air from the chamber of said casing through said conduit whereby said ther-

mostatic members will be subjected to the dry and wet bulb temperatures of the same current of air and each thermostatic member will be unaffected by the temperature to which the other is subjected. 35

15. A thermostatic regulator comprising laterally distortional bi-metallic thermo-flexible members subject respectively to the dry and wet bulb temperatures of the air, an energy-controlling device having a stationary contact member, a co-operating contact member pivotally mounted thereon normally resting by gravity upon said stationary contact member and provided with an upwardly extending arm, means movable relatively to said arm differentially operable by the lateral deflections of said thermo-flexible members to engage said arm and swing said movable contact member out of operative engagement with said stationary contact member and means for permitting said differentially operable means to be moved out of the path of said movable contact member arm whereby said movable contact member may be rotated about its pivot to permit free access to said stationary contact member. 40 45 50 55

In testimony whereof, we have signed our 60 names to this specification.

EDWARD W. COMFORT.
ALBERT W. THOMPSON.
